UNITED STATES PATENT OFFICE

113,148

DESIGN FOR A BAR MATERIAL FOR OPHTHALMIC MOUNTINGS

Edward M. Splaine, Southbridge, Mass., assignor
to American Optical Company, Southbridge,
Mass., a voluntary association of Massachu-
sets

Application April 15, 1938, Serial No. 76,545

Term of patent 14 years

To all whom it may concern:

Be it known that I, Edward M. Splaine, a citizen of the United States of America, residing at Southbridge, in the county of Worcester and State of Massachusetts, have invented a new, original, and ornamental Design for Bar Material for Ophthalmic Mountings, of which the following is a specification, reference being made to the accompanying drawing, forming a part thereof.

The figure in the drawing is a greatly enlarged perspective view of a piece of bar material for use in forming parts of an ophthalmic mounting and embodying my new design.

The characteristic features of the design reside in the provision of a surface having relatively narrow continuous faces adjacent the opposed longitudinal edges of the bar which lie substantially in the same plane and in the provision of

a corrugated face intermediate said continuous faces.

The bar material, designed as set forth above, when light impinges thereon, gives forth the appearance of two spaced ribbons of light which are reflected by the continuous faces adjacent the opposed longitudinal edges of the bar and an intermediate dull appearing surface produced by the corrugated portion of said bar. Said corrugated portion having a dull satin-like appearance as compared with the spaced ribbonlike reflected bands of light when viewed at a slight distance therefrom.

I claim:

The ornamental design for bar material for ophthalmic mountings, substantially as shown and described.

EDWARD M. SPLAINE.
